UNITED STATES PATENT OFFICE

HOWARD J. KERR, OF WESTFIELD, NEW JERSEY, ASSIGNOR TO THE BABCOCK & WILCOX COMPANY, OF BAYONNE, NEW JERSEY, A CORPORATION OF NEW JERSEY

FLUID CONTAINER

Application filed June 27, 1925. Serial No. 39,891.

My present invention relates to drums for steam boilers or the like, and particularly such drums when made by rolling a sheet of metal into cylindrical form with the edges 5 thereof abutting to form a butt joint. Such joints are usually covered by inner and outer straps riveted to the drum shell and, in order to prevent leakage, the edges of the straps are caulked against the drum shell. In some 10 cases, in steam boilers, tubes have their ends inserted in the drum through such straps.

In such drums, if the caulking is defective, the liquid from the drum will enter between the drum shell and the inner strap through 15 some defective point in the caulking and will then find its way through some opening through the drum shell (as at the shell joint itself, for instance), and may then flow to any point before appearing beneath the edge 20 of the outer strap. Consequently, when liquid does appear at the edge of the outer strap, it is impossible to tell where the leak in the caulking is, because the liquid may have traveled a long distance before it appears. The 25 same is true of leakage around the inserted tubes. Any leakage through the tube hole may travel a considerable distance before appearing at the edge of the outer strap, making it difficult to determine the point of 30 leakage.

One of the objects of my invention is to provide means by which leakage can be readily located. My invention will be best understood from the following description and the 35 annexed drawings, in which Fig. 1 is a cross section and Fig. 2 a side elevation of a steam boiler drum which I have chosen for purposes of illustration, Fig. 1 being a section on line 1—1 of Fig. 2; Fig. 3 is an enlarged view of a portion of Fig. 2; Fig. 4 is a section on line 4—4 of Fig. 3; Fig. 5 is a section on line 5—5 of Fig. 3; Fig. 6 is an enlarged section of the outer strap on line 6—6 of 40 Fig. 3; Figs. 7 and 8 are respectively cross section and side elevation of another form of drum which I have chosen for purposes of illustration, Fig. 7 being a section on line 7—7 of Fig. 8; Fig. 9 is an enlarged view 45 of a portion of Fig. 8; Fig. 10 is a section on

line 10—10 of Fig. 9, and Fig. 11 is a section on line 11—11 of Fig. 9.

Like reference characters indicate like parts throughout the drawings.

In Figs. 1 to 6, inclusive, 10 is a drum of 55 a type commonly used in steam boilers, the shell being formed of two semi-cylindrical portions with their edges butting. The butting edges are covered with inner straps 11, 12 and outer straps 13, 14, these straps being 60 fastened to the shell and to each other by rivets 16, in the usual manner. The edges at the joints usually do not quite contact, the space between them being indicated at 15. The edges of the inner straps 11, 12 65 are caulked against the drum shell 10 and the edges of the outer straps 13, 14 may also be caulked, though preferably I omit the caulking of the outer straps.

Through the straps 11, 13 extend tubes 70 17, 19, holes 18 and 19 in straps 11, 13 and holes 20 in the drum shell being provided for that purpose. Holes 20 are made slightly larger than holes 18, 19 and the tubes 17 have their ends expanded in holes 18, 19. 75

With the arrangement so far described, it is obvious that liquid finding its way past the caulking of the inner strap 11 will flow in an undirected course till it meets an opening through the drum shell, as the joint 80 15 between the edges of the drum plates, the holes 18, 19 or even a defective rivet which does not quite fill its holes. It will then flow beneath the outer strap 13 and will again flow in an undirected path till 85 it finds an opening beneath the outer edge of the strap 13. Because the course of the liquid is undirected, there is no means of locating the leak, because it may be near to or far from the point of appearance of 90 the liquid.

In order to direct the course of the liquid, I provide grooves in the surface between the strap and drum which will bring the liquid to the edges of the outer strap 13 at 95 a point closely adjacent the point of leakage. In Figs. 3 to 6, inclusive, grooves 21 are provided on the inner face of strap 13, extending from the joint 15 to the outer edges of the strap, between rows of rivets. 100

These grooves may be very shallow, say $\frac{1}{16}$ of an inch deep. In addition, grooves 22 extend from holes 18 to grooves 21. Grooves 21 extend to and through the edges of strap 13, but, if desired, may stop short of the edges, the liquid being then delivered so near the edges that when it appears it will be substantially at the point to which it would have been led, if the grooves 21 extended through the edges.

Similarly, the inner face of the inner strap 11 is provided with grooves 23 which parallel grooves 21. But grooves 23, in no case, extend through the caulked edges of strap 11, because obviously that would defeat the purpose of the caulking. If desired, the grooves 23 may be omitted. The grooves may be in the metal of the drum, instead of in the straps. Preferably, I close the joint 15 by spot welding at intervals, as at 15'.

With the arrangement described, any liquid passing the caulked edge of strap 11 at any point will shortly encounter one of the grooves 23 and will be led to the joint 15. The spots 15' will compel the liquid to flow into the groove 21 connecting with the part of the joint 15 between a pair of the spots 15' and will then be led to the edge of strap 13, at a point closely adjacent the point of leakage, so that this last-named point can be readily found and the defect remedied. Similarly, if leakage occurs around one of the tubes 17, the liquid passes through hole 20 and then enters one of the grooves 21, as before.

In the arrangement shown in Figs. 7 to 11, inclusive, the drum 25 is formed with a butt joint covered by outer strap 26 and inner strap 27, the joint itself being indicated at 28. This joint is closed at spaced intervals by the spot welds 28'. Grooves 29 extend across the surface between strap 26 and drum 25 (being cut either in the strap or the drum, as hereinbefore explained) and grooves 30 are cut either in strap 27 or the surface of the drum under strap 27, but stopping short of the caulked edges of strap 27. The operation of these grooves is as explained in connection with Figs. 3 to 6, inclusive.

While I have illustrated by invention in a drum having a longitudinal seam, it will be understood that it may be applied to any seam covered by a strap or the like, where it is desirable to lead the liquid leaking past a supposedly tight joint to the surface near where the leak occurs.

I claim:

1. A cylindrical drum having a butt joint and inner and outer straps covering said joint and riveted to the drum, with the edges of the inner strap caulked to form a tight joint between said edges and the drum, the outer strap and the drum having contacting

faces, and one of said faces having grooves therein extending from the edges of the drum joint substantially to the outer edges of the outer strap.

2. A cylindrical drum having a butt joint and inner and outer straps covering said joint and riveted to the drum, with the edges of the inner strap caulked to form a tight joint between said edges and the drum, the inner strap and the drum having contacting faces and one of said faces having grooves extending across it but not past the caulked edge and the outer strap and the drum having contacting faces, one of said faces having grooves extending across it substantially to the outer edges of said strap, each groove on the inside of the drum communicating with a groove on the outside of the drum through an opening through the shell of the drum.

3. A cylindrical drum having a butt joint and inner and outer straps covering said joint and riveted to the drum, with the edges of the inner strap caulked to form a tight joint between said edges and the drum, the inner strap and the drum having contacting faces and one of said faces having grooves extending across it but not past the caulked edge and the outer strap and the drum having contacting faces, one of said faces having grooves extending across it towards and through the outer edges of said strap, each groove on the inside of the drum communicating with a groove on the outside of the drum through an opening through the shell of the drum.

4. A cylindrical drum having a butt joint and inner and outer straps covering said joint and riveted to the drum, and tubes extending through said straps and the shell of the drum and expanded into the inner strap, with a clearance hole for the tube in the drum shell, the outer strap and the drum having contacting faces and one of said faces having grooves each extending from a tube hole substantially to the outer edge of said strap.

5. A cylindrical drum having a butt joint and inner and outer straps covering said joint and riveted to the drum, and tubes extending through said straps and the shell of the drum and expanded into the inner strap, with a clearance hole for the tube in the drum shell, the outer strap and the drum having contacting faces, and one of said faces having grooves therein, each extending from a tube hole towards and through the outer edge of said strap.

6. A cylindrical drum having inner and outer straps with a joint disposed within the limits defined by the edges of said straps, the edges of the inner strap being caulked to form a tight joint between said edges and the drum, the outer strap and the drum having contacting faces, and one of said faces having a groove leading from said joint substantially to an edge of said outer strap.

7. A cylindrical drum having a butt joint and inner and outer straps covering said joint and riveted to the drum, with the edges of the inner strap caulked to form a tight joint between said edges and the drum, the outer strap and the drum having contacting faces, and one of said faces having a groove therein extending from said joint substantially to an edge of said outer strap.
- 10 8. A cylindrical drum having a butt joint and inner and outer straps covering said joint and riveted to the drum, with the edges of the inner strap caulked to form a tight joint between said edges and the drum, the outer strap and the drum having contacting faces, one of said faces having a groove therein extending from said joint substantially to an edge of said outer strap, and the edges of said drum at said joint being welded together on opposite sides of said groove.
- 15 9. A cylindrical drum having inner and outer straps with a joint disposed within the limits defined by the edges of said straps, the edges of the inner strap being caulked to form a tight joint between said edges and the drum, the drum contacting with the faces of said inner and outer straps, one of the contacting faces of the inner strap and the drum having a groove extending from said joint towards but not past the caulked edge, and one of the contacting faces between the outer strap and the drum having a groove extending from said joint substantially to the outer edge of said outer strap.
- 20 10. A cylindrical drum having inner and outer straps riveted to the drum shell with tubes extending through said straps and shell and expanded into the inner strap with a clearance hole for the tube in the drum shell, the outer strap and the drum having contacting faces, and one of said faces having grooves therein, each extending from a tube hole towards and through the outer edge of said strap.
- 25 11. A cylindrical drum having inner and outer straps with a joint disposed within the limits defined by the edges of said straps, the outer strap and the drum having contacting faces, and one of said faces having a groove leading from said joint substantially to an edge of said outer strap.
- 30 12. A pressure container including an overlying reinforcing member in contact with the wall thereof, spaced passages between the wall and member and each leading to a point adjacent the exterior of the member, and dams defining sections of the drum wall to be served by the passages whereby said passages function as a tell-tale for leakage in the respective sections set off by the dams.
- 35 13. A pressure container having perforations in the wall thereof, a reinforcing member in contact with the surface of said container and having registering perforations, elements extending through the perforations
- in the wall and member and in fluid-tight relation with the container wall, and passages between the wall and member and leading from said perforations to points adjacent the exterior of said member to indicate leakage.
